for illustrative purposes only and form no part of the claimed design. Broken lines formed by equal length dashes show unclaimed subject matter. Broken lines formed by unequal length dashes (i.e., dash-dot) define bounds of the claimed design. Broken away symbols having a jagged element are not part of the claimed design and show unspecified lengths of the portion are possible and that no particular length of the portion is being claimed. Such break lines illustrate a symbolic break in length, and the appearance of any portion of the article between the break lines forms no part of the claimed design.
